Patented Nov. 20, 1956

179,233

RING

Edward Abrams, Toronto, Ontario, Canada

Application January 30, 1956, Serial No. 39,960

Term of patent 14 years

(Cl. D45—10)

FIG. 1

FIG. 2

FIG. 3

Figure 1 is an **elevational** view of one side of a ring embodying my new design, the initial element being illustrated in broken lines to indicate variability of the initial;

Figure 2 is a front elevational view; and

Figure 3 is a perspective view thereof particularly showing the second side of the said ring.

My design is characterized by a single solid initial element located between the slender corner columns and below the claws of the specific central gem-receiving unit.

I claim:

The ornamental design for a ring, as shown and described.
